UNITED STATES PATENT OFFICE.

DANIEL W. NOLAN, OF SPRINGFIELD, ILLINOIS. ASSIGNOR TO MARY J. NOLAN, OF SPRINGFIELD, ILLINOIS.

AUTOMATIC STOCK-SPRAYER

1,033,289.

Specification of Letters Patent.

Patented Mar. 4, 1913.

Application filed February 21, 1912. Serial No. 679,092.

To all whom it may concern:

Be it known that I, DANIEL W. NOLAN, a citizen of the United States, residing at Springfield, in the county of Sangamon and State of Illinois, have invented a new and useful Automatic Stock-Sprayer, of which the following is a specification.

This invention is a modification and improvement of the invention set forth in my application S. N. 677,702 automatic stock-sprayer, filed February 15, 1912.

The purpose of the present invention is to provide means adapted to spray the animal from above and below and to provide improved means for controlling the supply of liquid to the sprayer-heads.

The invention is illustrated in the annexed drawing to which reference is hereby made and is hereinafter described and the novel features thereof are finally recited in the appended claims.

Figure 1 is a combined front elevation and sectional view of the apparatus and Fig. 2 is an enlarged horizontal section on the line 25 X--X of Fig. 1.

Similar reference numerals designate like parts in both views.

The main frame is a rectangular structure comprising four corner posts 1 preferably of gas pipe. The posts are supported on stationary blocks 2. Horizontal rails 3 connect the posts and give rigidity to the structure. A tank 4 mounted on the main frame contains the liquid which is to be used. Horizontal diagonal bars 5 are adapted to slide in slots 6 in the posts 1. Horizontal transverse bars 7 are adapted to slide in slots 8 in the posts 1 and support a platform 9 having a central opening 10 accommodating the lower sprayer head 35 when the platform is depressed. Vertical rods 12 within the posts 1 connect the horizontal transverse bars 7 with the diagonal bars 5 and are equipped with nuts 12^a which may be screwed upward or downward on the rods to control the tension of the springs 14 underlying the diagonal bars. Circular stationary blocks 13 within the posts 1 support springs 14 on which the diagonal bars 5 rest. The blocks 13 have holes in which the rods 12 slide freely. A vertical valve rod 15 is connected with the diagonal bars 5 at the point of their intersection by nuts 15^a and has a polygonal part 15^b adapted to accommodate a wrench for turning the rod as

hereinafter described. A valve body 16 suitably located within the tank has a main chamber 17, main outlet 18, an upwardly tapered valve seat 19, an auxiliary chamber 20, an auxiliary outlet 21, and a downwardly tapered valve seat 22. A ball 23 connected with the valve rod 15 fits on the valve seat 19 and is movable downwardly to open the valve and upwardly to close the valve. A ball 24 fits on the seat 22 and is movable upwardly to open the valve and downwardly to close the valve.

An approximately U shaped spring 25 is bent to form eyes 26 accommodating a bolt 27 connecting the spring with a stationary standard 28. The spring also has prongs 29 extending through transverse holes in the wings of a wing-nut 30 which screws onto the valve rod 15. An upwardly extending stem 31 is connected with the ball 24. Nuts 32 adjustably connect the stem 31 with the spring 25. The spring 25 when under tension acts to press the ball 24 downward to cause it to rest evenly on the seat 22 and also acts to press the ball 23 upwardly to cause it to rest evenly on the seat 19 so that accurate seating of both balls is assured. The proper tension of the spring may be attained by loosening the nuts 15^a and turning the rod 15 in the wing-nut 30 85 by means of a wrench used on the part 15^b, to increase or diminish the tension of the spring as may be required. A sprayer head 33 communicates with the outlet opening 18.

A pipe 34 in communication with the outlet opening 21 extends downwardly within one of the posts and outwardly from the post and under the platform 9 to the center of the apparatus and is equipped with a sprayer head 35 which is below the platform 90 when the platform is in its normal raised position and which occupies the opening 10 when the platform is depressed. The purpose in locating the pipe 34 within the posts 1 is to prevent stock from rubbing against the pipe and loosening the connections. The platform protects part of the pipe 34 and the sprayer head 35 which are below the platform.

In practical use the apparatus will be 105 located in a gate opening or in any other suitable opening of a fence, separating two inclosures so that the animals passing from one inclosure to the other will go over the platform. The weight of the animal going 110

onto the platform will compress the springs 14 and cause the platform and the diagonal bars 5 to descend and push the rod 15 downward to open communication with the chamber 17 and the rod 15 pushing downward on the spring 25 will raise the ball 24 to open communication with the chamber 20 and the liquid contained in the tank will flow into both chambers alike. The liquid entering 10 the chamber 17 will flow through the sprayer head 33 and will be sprayed on top of the animal and the liquid from the chamber 20 will flow through the pipe 34 to the sprayer head 35 and will be sprayed upward onto 15 the animal. Skin diseases and vermin are very likely to occur on the underside of the animal's body. There is great practical advantage in the two sprayer heads to apply the liquid both from above and below and 20 distribute it equally over the entire body of the animal thereby avoiding the necessity for immersing the animal and resulting in economical use of the liquid and saving much labor in the treatment of the animal. 25 Immersing has been commonly practised but is objectionable not only on account of the labor involved, but because the liquid in which the animal is immersed attacks the eyes and the membranes of the nose and 30 throat and is injurious to the animals. The spraying affords effective treatment and is not injurious to the animal's eyes or membranes. If it be desired to control the operation of the sprayer by hand, that may be 35 effected by means of a lever 36 suitably connected to operate the valve rod 15.

Having fully described my invention what I claim as new and desire to secure by Letters Patent is:

40 1. In an apparatus of the class described, the combination of a tank support; a tank adapted to contain liquid; a valve-body mounted in the tank and having two contiguous chambers; outlet devices in communication with the respective chambers of the valve-body; a downwardly-acting sprayer in communication with one outlet device; an upwardly-acting sprayer in communication with the other outlet device; 45 two valves controlling communication with the respective chambers of the valve-body; a springy connection normally acting to

hold both valves on their seats, and valve actuating means connected with said springy connection. 55

2. In an apparatus of the class described, the combination of a tank support; a tank adapted to contain liquid; a two-chamber valve-body in communication with the tank; outlet devices in communication with the respective chambers of the valve-body; vertically opposite sprayers in communication with said outlet devices respectively; two valves controlling admission of the liquid to the valve chambers respectively; a lever 60 connecting said valves; and a vertically adjustable valve rod actuating both valves simultaneously.

3. In an apparatus of the class described, the combination of a tank support; a tank 70 adapted to contain liquid; a two-chamber valve-body in communication with the tank; outlet devices in communication with the chambers of the valve-body respectively; vertically opposite sprayers in communication with said outlet devices respectively; a pair of valves controlling communication with the chambers of the valve-body respectively; a springy lever connecting the valves; a screw-threaded valve rod; and a 75 nut on the screw-threaded valve rod and capable of adjustment to control the tension of the springy lever.

4. In an apparatus of the class described, the combination of a tank support; a tank 80 adapted to contain liquid; a two-chamber valve-body in communication with the tank and having an inlet opening and an outlet opening for each chamber; two oppositely movable closures controlling admission to 85 the chambers of the valve-body respectively; an oscillative lever connecting said closures; outlet devices in communication with the respective chambers of the valve-body; and vertically opposite sprayers in communication with said outlet devices. 90

In witness whereof, I have hereunto signed my name at Springfield, Illinois, this nineteenth day of February, 1912.

DANIEL W. NOLAN.
